(57) **CLAIM**

The ornamental design for a deer blind, as shown and described.

DESCRIPTION

FIG. 1 is a perspective view of a deer blind showing our new design;

FIG. 2 is a top view thereof;

FIG. 3 is a side elevational view thereof;

FIG. 4 is an end elevational view thereof; and,

FIG. 5 is a bottom view thereof.

The broken line showing of a roof in FIGS. 1-4 is included for the purpose of illustrating portions of the deer blind and forms no part of the claimed design.
